UNITED STATES PATENT OFFICE.

JULIUS SWANBERG, OF CHICAGO, ILLINOIS, ASSIGNOR TO SWANBERG MANUFACTURING COMPANY, OF CHICAGO, ILLINOIS, A CORPORATION OF ILLINOIS.

DESIGN FOR A PENCIL OR SIMILAR ARTICLE.

Application filed June 11, 1923. Serial No. 6,469. Term of patent 14 years.

To all whom it may concern:

Be it known that I, JULIUS SWANBERG, a citizen of the United States, and residing in the city of Chicago, county of Cook, and State of Illinois, have invented a new, original, and ornamental Design for a Pencil or Similar Article, of which the following is the specification, reference being had to the accompanying drawings, forming a part thereof.

In the drawings:

The figure is an elevational view of a pencil illustrating the design embodying my invention.

I claim:

The ornamental design for a pencil or similar article as shown.

JULIUS SWANBERG.
